CLAIM

The ornamental design for a base for dental lamps, as shown.

DESCRIPTION

FIG. 1 is a top, front and side perspective view of a base for dental lamps, showing my new design;

FIG. 2 is a front elevational view thereof;

FIG. 3 is a side elevational view thereof from the left of FIG. 2;

FIG. 4 is a side elevational view thereof from the right of FIG. 2;

FIG. 5 is a rear elevational view thereof; and,

FIG. 6 is an enlarged top plan view thereof.
